PROCESS OF FORMING LIQUID
HYDROCARBONS

Georges Francis Michot-Dupont, Vincennes,
France, assignor to Physical Chemistry Re-
search Cy, New York, N. Y., a company of
Delaware

Application July 5, 1929, Serial No. 376,008
In Belgium June 4, 1929

3 Claims. (Cl. 204—31)

The present invention relates to methods and apparatus for transforming coal into low-boiling mixtures similar to gasoline.

Divers methods are now known for transforming mixtures of unsaturated gases of the acetylenic and ethylenic series into low-boiling saturated compounds by hydrogenation in the presence of a suitable catalytic agent. These methods suffer from the serious disadvantage of requiring the preliminary production of unsaturated gases and are further rendered impracticable by the difficulty experienced in finding a catalyst which will withstand the "poisoning" action of sulphur and similar elements contained in the gas mixtures to be treated.

One of the objects of the invention is to provide a process and an apparatus operative to transform the organic portion of a solid combustible of the nature of coal into gases and to then transform said gases into a low-boiling hydrocarbon mixture.

Another object is to provide catalytic means which will be unaffected by the "poisonous" elements contained in gases prepared from coal.

Further objects will appear in the course of the detailed description now to be given with reference to the accompanying drawings, in which:

Fig. 1 is a diagrammatic section through one illustrative embodiment of the invention;

Fig. 2 illustrates, diagrammatically, another possible form of the invention.

Fig. 3 is a section taken on line 3—3 of Fig. 2.

The invention may, of course, be carried out in any one of a number of possible operating structures and consists of the following steps. Coal or any similar solid combustible is heated in suitable, closed, retorts first at a temperature of about 500° C. so as to drive off the more volatile ingredients and then at a temperature of approximately 900° so as to produce a semi-coke, the combined gases so produced and containing hydrogen, methane, carbon monoxide and dioxide, benzol, toluene, xylene, etc. being conducted into a suitable reaction chamber to be mentioned further on. The semi-coke resulting from this operation is then treated with steam under the usual conditions for producing water-gas, and the carbon monoxide and hydrogen so formed are conducted into the same reaction chamber used for receiving the volatile matter distilled from the closed retorts. Finally hydrogen in variable quantities—about 1600 liters for each ton of coal originally-treated is introduced into the reaction chamber hereinabove mentioned, and the combined gases i. e. coal gas, water gas

and supplementary hydrogen, are exposed at atmospheric pressure and at temperatures which may vary from room temperature to 600° C., to the catalytic action of either (1) static field at about 80,000 to 100,000 volts, or (2) ultra-violet light or (3) an alloy composed of nickel and tin in equal proportions admixed with a trace of mercury.

The electrostatic field and the ultra-violet light, when used as catalysts are, obviously, not affected by the sulphur and other catalytic "poisons" contained in the gas mixture. Similarly the nickel, tin, mercury alloy—the mercury, it is to be noted appears only in traces—is remarkably immune to the action of these latter substances and, when used in the form of shavings or powder, retains its activity practically indefinitely. The greater part of the activity of the catalytic alloy appears to be due to the tin-mercury combination, a catalyst composed of tin alone and carrying traces of mercury operating to catalyze the reaction. However, the tin-mercury catalyst has too low a melting point and when operating at higher temperatures it is desirable to add nickel in substantially the proportions indicated. The nickel, besides raising the melting point of the alloy, appears to improve its catalytic quality. In actual operation while the electrostatic field is found to catalyze the reaction when used alone, better yields are obtained by combining the action of ultra-violet rays therewith. Similarly, the action of the metallic catalyst is improved by the adjunction of an electrostatic field or of ultra-violet light or of both. The temperature of the reacting gases should not exceed 600° C. since, above this temperature, the yields become very poor.

The reactions taking place in the reaction chamber appear to be the following.

The carbon monoxide and the hydrogen in the water gas enter into equilibrium in accordance with the equations.

The homologues of methane (and of ethane) in the coal gas appear to undergo changes similar to those of methane in the presence of the hydrogen and the catalytic agent in the reaction chamber. The final product is a mixture of saturated and of unsaturated compounds having approximately the same properties as natural

hydrocarbon oils, the proportions of heavy and light fractions varying with the nature of the solid combustible used.

It is to be understood, of course, that instead of converting the semi-coke resulting directly from the destructive distillation of a certain quantity of coal into water-gas, separate plants for effecting these operations may be used. In practice, however, it is found that the conversion of the coke residue, resulting from the retorting of the coal into water-gas, yields a gas mixture for the reaction chamber eminently suitable for conversion into a liquid hydrocarbon mixture.

Referring now to Fig. 1 of the drawings, there is shown a plant capable of carrying out the above described process and consisting of a furnace chamber *a*,—a grid *b* adapted to support the coke to be converted into water-gas and provided with the desired, limited, quantity of air via adjustable air-inlet *c*,—charging and discharging assemblies *d*¹ and *d*² adapted to be opened separately for charging coke and for removing cinders,—a boiler *e* positioned in the walls of chamber *a* and feeding a pair of conduits *e*¹ and *e*², conduit *e*³ feeding steam under the coke-bed supported on grid *b* so as to provide the necessary water vapor for forming water-gas, while conduit *e*¹ feeds a group of iron tubes *e*² positioned in the hot zone above the coke, which tubes react with the steam passing therethrough (tubes *e*² may be replaced by retorts filled with iron shavings) to form hydrogen and iron oxide, the hydrogen passing into reaction chamber *j*,—retort *f* for destructively distilling coal at a temperature of about 500° C., the products of this distillation passing out through a conduit *f*¹ into reaction chamber *j*,—a receiver *g* adapted to collect the heavy portions of the coal distillate and deliver the latter to a "cracking" retort *h* discharging cracked gases via conduit *g*¹ to the reaction chamber,—a conduit *i* for conducting the water-gas formed above grid *b* to chamber *j*,—a discharge conduit *j*¹, having in series therewith a fan *j*², heating coils *j*³ positioned above and below retorts *f*, *h* and adapted 45 to heat the final product to temperatures graded downward from about 300° C., and a cooling coil *j*⁵,—a pair of electrodes *k*¹, *k*² adapted to be connected to an electrostatic machine *k*,—and a source of ultraviolet light *s* positioned to send a beam through a quartz window in the wall of chamber *j*.

The manner in which the above apparatus functions has been suggested in the course of its description. If the nickel-tin-mercury alloy is to be used, it is placed inside chamber *j*. Otherwise, either the static field alone, or the ultraviolet light, or both are relied upon to catalyze the reaction, the final product being drawn off at *j*⁵.

The above described apparatus has the disadvantage of requiring transportation of the coke formed in retorts *f*, *h* to grid *b*. This latter operation is avoided in the continuously operating type of apparatus represented in Fig. 2 consisting of a furnace chamber *a*, closed by an upper wall *a*¹,—a charging hopper *l* of sufficient height to permit the broken coal piled therein to form a gas seal,—low temperature retorting chamber *m* operating at about 500° C. and provided with a gas discharge conduit *m*¹ communicating with reaction-chamber *j*¹,—high temperature retorting chamber *n* receiving the material discharged from *m* and operating at about 900° C., the gases issuing from chamber *n* discharging via conduit *n*¹ into reaction chamber *j*¹,—a conical grid *o* receiving the coke residues

from *n* and provided with steam from a conduit *e*³ for converting the coke into water-gas,—an iron, serpentine coil *e*² positioned just outside hopper *o* and adapted to convert steam fed thereinto into iron oxide and hydrogen at about 800° C., the hydrogen entering chamber *j*,—a rotatable shaft *p* fitted with rakes *p*¹ and *p*² adapted to assure downward movement of the charge,—a plurality of reaction chambers *j*¹, *j*², *j*³, *j*⁴ connected by transverse conduits and adapted to slow down the rate at which the reacting gases flow through the apparatus, chambers *j*¹ and *j*² being positioned so as to operate at about 600° C. while chambers *j*³ and *j*⁴ are at about 300° C.,—a scrubber *i*¹ of any convenient design receiving the water gas emanating from the coke bed resting on grid *o* and delivering via fan *i*² (which serves to draw these latter gases through *i*¹) to chamber *j*¹, a by-pass *i*³ being provided for delivering any water gas excess together with a limited quantity of air entering through valve *i*⁴ to the combustion chamber,—means for creating a static field in at least one of the reaction chambers of the *j* series (*j*², for example) comprising a pair of insulating walls *q*¹, *q*² traversed by a rectilinear electrode *r*, and an electrostatic machine grounded at one terminal and connected to electrode *r* at the other,—and a source of ultra-violet light *s* sending a beam through a quartz window in the wall of chamber *j*².

In this form of apparatus, coal is fed at *l*, coked at *m* and *n*, converted into water-gas at *o* under the action of the steam jet introduced under grid *o*, and discharged in the form of ash through *d*². The coal gas issuing from chambers *m* and *n*, the water-gas emanating from *o*, and the hydrogen discharged from coil *e*² pass into the reaction chambers of the *j* series, and are converted by either the nickel-tin-mercury alloy, an electrostatic field, ultra-violet light or any permutation or combination of the latter into a liquid hydrocarbon discharging at cooling coil *j*⁶.

What I claim is:—

1. The process of forming liquid hydrocarbons from a mixture of water-gas and volatile gases derived from carbonaceous material which includes heating a mixture of said gases and subjecting the mixture, while in a heated condition, to the combined action of ultra-violet light and an electrostatic field of the type produced by voltages of the order of 80,000 to 100,000 volts.

2. The process of forming liquid hydrocarbons from a mixture of water-gas and volatile gases derived from carbonaceous material which includes heating a mixture of said gases, subjecting the mixture, while in a heated condition, to the combined action of ultra-violet light and an electrostatic field of the type produced by voltages of the order of 80,000 to 100,000 volts, and adding hydrogen to the mixture being treated to produce a mass action effect on the reaction taking place under the influence of said ultra-violet light and said electrostatic field.

3. The process of forming liquid hydrocarbons from a mixture of water-gas and volatile gases derived from carbonaceous material which includes heating a mixture of said gases to a temperature in the neighborhood of 600° C., and subjecting the mixture, while in a heated condition, to the combined action of ultra-violet light and an electrostatic field of the type produced by voltages of the order of 80,000 to 100,000 volts.

GEORGES FRANCIS MICHOT-DUPONT. 78
